UNITED STATES PATENT OFFICE.

REUBEN ALDEEN, OF ROCKFORD, ILLINOIS, ASSIGNOR TO NATIONAL LOCK CO., OF ROCKFORD, ILLINOIS, A CORPORATION OF DELAWARE.

RADIO TUNING DEVICE.

Application filed January 25, 1926. Serial No. 83,494.

My invention relates to radio apparatus and particularly to the control mechanism by which the condensers may be adjusted for tuning purposes.

5 The object of my invention is to provide means for operating the various condensers from a single control and includes provisions for relative adjustment between the condensers as well as adjustment of the various condensers together as a unit, and also a novel and reliable form of connection between the condensers and the control knob.

10 In order to facilitate an understanding of my invention and the apparatus used for carrying out the same, reference is directed to the accompanying drawings, from which, when considered in connection with the following description, the construction, operation, and many of the advantages will be 15 readily understood and appreciated.

20 Referring to the drawing:

Fig. 1 is a top plan view of my invention shown in connection with three condensers of a continuous wave receiving set,

25 Fig. 2 is a front view of the same,

Fig. 3 is a fragmentary vertical section of the operating device taken on the line 3—3 of Fig. 2 and showing the condenser unit B in side elevation, and

30 Fig. 4 is a longitudinal sectional view on the line 4—4 of Fig. 3.

Like symbols of reference indicate like parts in each of the figures of the drawing.

In the drawings which I have used to illustrate my invention, I have shown three reactance units such as the variable type condenser which I have indicated as A, B, and C, and while these units are used for illustrative purposes, I do not limit myself to that exact number nor to the type shown, as various standard condensers which will produce a desired result may be included in the apparatus with satisfying results.

The front of the apparatus consists of a 45 front wall 11, and the front and rear upright standards 12 and 13 respectively are mounted upon a base plate 14 by screws 16 or in any other suitable manner, and the rotating part of the condenser B is carried on a shaft 17 which extends through a small bushing 18, and said bushing is secured against the standard 12 by nuts 19 and 21, so as to provide a bearing for the said shaft. In front of the bushing 18 on the shaft 17 is a sleeve 22 provided with a circumferential groove 23 in

which is seated the surrounding wall of an opening in a plate 24, which is connected to the front plate 12, as later described.

The forward end of the shaft 17 is bored and tapped to receive a screw having a tapered head, the end of the shaft bore being similarly tapered and provided with a number of saw cuts 28 extending diametrically thereof, so that the shaft may be expanded by the screw head. A pulley 29, formed of 60 bakelite or some other electrical nonconductor is rotatably carried by the sleeve 22, and has secured on its front face, by any suitable means, an internal gear ring 32, having internal teeth 33 which mesh with a pinion 35 65 fixed on a shaft 36, and said internal gear ring can be rotated together with the pulley 29 as the shaft 36 extends through the partially circumferential opening 37, while the pinion 35 is free to move within the recessed 70 portion 40 in said pulley.

The rear end of the shaft 36 is supported through the sleeve 30 in an opening 30' in the plate 24, and its forward end extending beyond the front wall 11 has a controlling knob 80 38 secured there to by a set screw 39. A sleeve 41 surrounding the shaft has secured thereto another operating knob 42, which is secured to the sleeve 41 by a nut 43, the outside contour and appearance of the said operating knobs presenting the appearance of a single unit. Immediately in front of the pulley 29 and the internal gear 32 carried by it is another pulley 44 formed preferably of 85 bakelite or some other electrical nonconductor. This pulley is also provided with a ring gear 46 which has internal teeth 33, which in turn mesh with the teeth 47 on the pinion 48 fixedly secured to the sleeve 41 on the shaft 36, so that the same is free to operate through 90 the medium of the control knob 42 and independent of the ring gear 32 connected to the pulley 29. The member 44 is recessed as at 95 49, and a bushing 51 extends over the shaft 17 and through the opening 52 in the extended U-shape plate 53 whose vertical legs 54 pass over the plate 24 and are together connected with the standard 12 through the portions 56 and 57 by means of the screws 58.

The recessed portion 49 is further extended 100 so as to form a recess 59 in the member 44 and into this recess fits the finger 61 which has a circular portion 62 fitting into the annular groove 63 in the bushing 51, and a bolt 65, having the sides of its head tapered as 105 66, secured to the member 44 by a nut 67.

shown at 64 is screwed into the threaded hole 27 at the end of the shaft 17, and as the tapered head of said screw bears against the portions of the shaft included between the 5 saw cuts 28, it will tend to press the said material included between said saw cuts outwardly, so as to securely clamp the bushing 51 to the end of the shaft 17 and thus insure the turning of said shaft when the member 44 10 is turned.

The pulleys 29 and 44 are each provided with a rear integral shoulder 66 and 67 respectively while between the said drums and their respective ring gears 32 and 46 are insulating washers 68 and 69, as later explained.

In the front face of the pulley 29 is a slot 70 into which a dowel pin 70', fixedly secured in the rear of the pulley 44, extends, and the 20 lost motion between the walls of the said slots or holes 70 provides for the adjustment between the said pulleys.

The shafts which carry the rotatable plates on the condenser units A and C are each provided with a pulley 71 and 72 respectively which have the hubs 73 and 74 formed integrally therewith, and are adapted to be fixedly secured to said shafts by means of the set screws 75. Each of these shafts which extend through the front wall 11 are provided with bearing members 76 and 77 which are secured to said shafts between set screws 78, and said bearing members are provided at their extreme forward ends and in front of 35 the front wall with indicators 87 secured by means of the screws 88 extending into the said shafts.

The pulley 29 is provided with a steel belt 79 which passes over and around the pulley 71 on the condenser A, and in order to provide for the adjustment of the plates of the condenser A with the plates of the condenser B, a U-shaped clamping member 81 is passed over said pulley and fixed securely thereto by 45 the screws or bolts 82, while the belt which passes between the said pulley and the U-shaped member is adjusted to position on the pulley through the set screw 83 in the end thereof, which, when tightened will prevent 50 any slipping of the belt.

The pulley 44 is also provided with a steel belt 84 which passes over the pulley 72 and is provided with a U-shaped member 81 for adjusting purposes, and is the same as that 55 which has just been described in connection with the condenser unit A.

Each of the pulleys 29 and 44 are provided with one or more pins 90 for engaging holes in the belts 79 and 84 to prevent the belts 60 from slipping thereon.

The operation of my improved device is as follows: If the condenser units have been previously set so that the exact adjustment has been provided for tuning in on different 65 wave lengths, the control knobs 38 and 42

may be turned simultaneously, as though there were but a single knob for controlling the entire apparatus. This can very readily be accomplished by placing the thumb and forefinger upon the dividing line between the 70 said knobs which I have designated by the characteristic 86, so that the shaft 36 and the sleeve 41 surrounding the same will be turned simultaneously and since the teeth 47 on the ring gear 46 are engaged by the teeth on the pinion 48, which ring gear is securely fixed to the pulley 44, and the teeth 33 on the ring gear 32 are engaged by the teeth 34 on the pinion 35 operating on the shaft 36 which is fixedly secured to the pulley 29, said pulleys 80 will be turned at the same rate of speed, and the pulley 71 on the condenser unit A, and the pulley 72 on the condenser unit C will be both operated at the same rate of speed, through the belts 79 and 84, so that the movable plates therein will assume the same position with regard to the stationary plates in each of the units A and C. The finger 61, being firmly set in the recess 59, and its circular portion 62 being clamped securely to the 90 shaft 17 by means of the screw 65, pressing the portions of said shaft between the saw cuts 28 outwardly, the said shaft 17 and the movable plates on the condenser unit B connected therewith, will, in like manner, be 95 turned simultaneously with the shafts carrying the moving plates on the condenser units A and C.

If, however, it is desired to operate the condenser unit A and the condenser units B 100 and C independent of each other, in order to secure an adjustment for any given wave length, the operating knob 38 is turned so as to turn the shaft 36 which will rotate the pinion 35 whose teeth 34 mesh with the teeth 105 33 on the internal gear 32, and the said internal gear being fixedly mounted on the pulleys 29, the said pulley will be rotated so as to move the belt 79 which in turn will operate the pulley 71 on the shaft of the condenser unit A, and thus turn the rotatable plates 110 therein. After this adjustment has been secured, the operator may then turn the operating knob 42 which turns the sleeve 31 on which the pinion 48 is located, so that the teeth 47 on the internal gear 46 are moved thereby, and as the said internal gear is fixedly secured to the pulley 44, the belt 84 carried thereon will be moved so as to operate the pulley 72 carried on the shaft upon which the movable plates of the condenser unit C 115 are located. During the rotation of the pulley 44, the finger 61 which is located in the recess 59 has likewise been rotated, and as the said finger is fixedly secured to the shaft 120 17 through the medium of the screw 65, as hereinbefore explained, the movable plates which are connected to the said shaft 17 will be moved in unison with the plates on the condenser unit C.

It is believed that my improved tuning device and a preferred means for carrying the invention into effect and its advantages will be appreciated from the foregoing specification without further description, and it will be manifest that the structural details illustrated and described may be varied within wide limits without exceeding the scope of the invention as defined in the following 10 claims.

I claim:

1. A radio tuning device comprising a plurality of variable reactance units, a shaft for each unit, one of said shafts having a 15 sleeve, pulleys on said sleeve, a pulley on each of the shafts of the other units, means operatively connecting each of the last named pulleys with one of the pulleys on said sleeve, an internal gear ring on each of the pulleys 20 on said sleeve, and means engaging said gear rings to operate said other units.

2. A radio tuning device comprising a plurality of variable reactance units, a shaft for each unit, one of said shafts having a 25 sleeve, pulleys on said sleeve, a pulley on each of the shafts of the other units, means operatively connecting each of the last named pulleys with one of the pulleys on said sleeve, an internal gear ring on each of the pulleys 30 on said sleeve, a shaft having a pinion engaging one of said gear rings to operate the pulley to which it is connected, a sleeve on said shaft, a pinion on said sleeve engaging another of said gear rings to operate the pulley 35 to which it is connected, and means on said shaft and sleeve to independently operate them to adjust the units.

3. A radio tuning device comprising a plurality of variable reactance units, a shaft 40 for each unit, one of said shafts having a

sleeve, pulleys on said sleeve, a pulley on each of the shafts of the other units, means operatively connecting each of the last named pulleys with one of the pulleys on said sleeve, means providing lost motion between the 45 pulleys on said sleeve, and a single unit control member for operating the pulleys on said sleeve to operate said other units, said member having a relatively adjustable part thereof separately connected to one of said 50 pulleys to provide relative adjustment between the pulleys on said sleeve.

4. A radio tuning device comprising a plurality of variable reactance units, a shaft for each unit, pulleys on one of said shafts, 55 a pulley on each of the shafts of the other units, means operably connecting each of the last named pulleys with one of the pulleys on the first shaft, a gear ring on each of the pulleys on the first shaft, and means engaging said gear rings to operate said other units.

5. A radio tuning device comprising a plurality of variable reactance units, a shaft for each unit, pulleys on one of said shafts, a pulley on each of the shafts of the other 65 units, means operatively connecting each of the last named pulleys with one of the pulleys on said first shaft, a gear ring on each of the pulleys on said first shaft, a shaft having a pinion engaging one of said gear rings 70 to operate its respective pulley, a sleeve on the latter shaft, a pinion on said sleeve engaging another of said gear rings to operate its respective pulley, and means for independently operating said shaft and sleeve to 75 adjust said units.

In witness of the foregoing I affix my signature.

REUBEN ALDEEN.
